J. L. MOORE,
TOY VEHICLE.

1,157,171.

Patented Oct. 19, 1915.

UNITED STATES PATENT OFFICE.

JOHN L. MOORE, OF NEW YORK, N. Y., ASSIGNOR TO FERDINAND STRAUSS, OF YONKERS, NEW YORK.

TOY VEHICLE.

1,157,171.

Specification of Letters Patent.

Patented Oct. 19, 1915.

Application filed June 23, 1915. Serial No. 35,764.

To all whom it may concern:

Be it known that I, JOHN L. MOORE, a citizen of the United States of America, residing at New York city, Manhattan borough, county and State of New York, have invented certain new and useful Improvements in Toy Vehicles, of which the following is a full, clear, and exact description.

10 This invention relates to toy-vehicles designed for the amusement of children.

15 My improved toy is arranged so that a child may push or pull it along the street, floor, or the like, and, while the toy is in motion, a bell will ring in combination with the movement of a figure, carried by the toy arranged to be rocked to and fro by the movement of the support therefor. The various moving parts of the toy will tend to 20 amuse a child when operating in unison.

25 A further object of the invention is to provide a toy, of the character above described, which is of durable construction and not easily broken.

30 These results I obtain by means of a simple structure having no delicate parts which are likely to break with ordinary usage.

35 I will now proceed to describe my invention in detail, the essential features of which will be summarized in the appended claims, reference being had to the accompanying drawing, forming part hereof, wherein—

40 Figure 1 is a side elevation, partly in section, of a toy embodying my improvements; Fig. 2 is an enlarged cross-sectional view thereof, the section being taken on a line 2—2 in Fig. 1; Fig. 3 is a cross-sectional view, the section being taken on a line 3—3 in Fig. 1, looking in the direction of the arrow; Fig. 4 is a top plan view of my improved toy, the figure and a rear wheel being omitted; and Fig. 5 is a modified form of 45 a rear axle supporting means.

45 As herein embodied, my invention comprises a frame 1 which supports a front wheel 2, rear wheels 3 (one only being shown), a bell 4 and an oscillating table or platform 5. The frame 1 consists of side members 6, and one end member 7, all made 50 in one piece. The frame 1 is open at the end 8, said open end supporting or receiving the front wheel 2, as shown. The rear wheels are secured to a rotatable axle 9 having a crank 10 which, by means of a link 11, rocks 55 or oscillates the table or platform 5. The

table 5 is pivotally supported by plates 12 extending upwardly from the frame-members 6, pins 13 being employed to pivotally connect the table and plates. The bell 4 is carried by a yoke-frame 14 pivotally secured, by rivets 15 or the like, to the frame-members 6. One leg of the yoke-frame 14 carries an arm 16 which by means of a link 17 is connected to the table 5. To the axle 18 of the front wheel 3, I pivotally attach a yoke 19 which by means of a link 20 is connected to the movable arms 21 (one only being shown) of a figure 22 carried by the platform or table 5. A cross-bar 23 (Fig. 4) on the link 20 is long enough to engage both 70 arms 21 of the figure 22.

75 To push or pull the vehicle, I employ a handle 24 having a forked end consisting of two resilient arms 25, having inturned ends 26, to releasably engage openings 27 in the frame-members 6.

80 The axle 9 may be mounted in the frame members 6, as shown in Fig. 1, or in plates 28, as shown in Fig. 5, which extend from the frame-members 6. When the toy is pushed or pulled the rotation of the axle 9 will rock the table or platform 5, imparting to the figure 22 a movement to and fro. The to-and-fro movement of the figure 22 will impart to the pivotal yoke 19 a similar 85 movement, the object of which is to convey the idea that the figure is propelling the vehicle by a push-and-pull movement. In combination with the above-mentioned movements the yoke-frame 14 will be rocked upon 90 its pivotal points back and forth, causing the bell 4 to ring. The handle 24 may be disengaged from the frame by spreading the arms 25 to cause the ends 26 to leave the openings 27 in the frame-members 6.

95 The above described structure will produce a pleasing toy, and notwithstanding the fact that a child will push the toy, it will have the appearance of a self-propelled vehicle due to the combined movement of the figure and front yoke 19. Furthermore, as the yoke 19 and yoke-frame 14 will move in unison, but in opposite directions, a pleasing effect is produced.

100 As the figure 22 is supported by a resilient or yieldable post or wire 29, the said post will yield to the strain of moving the yoke 19. In other words the figure will not only be rocked to and fro bodily but will also have an additional bending movement due 105 110

to its yieldable support 29 giving the appearance of the exertion of energy to propel the vehicle. I may, as a variation, rigidly secure the yoke 19, instead of pivoting same, in which case the figure 22 will have a more pronounced back and forth movement.

Having now described my invention, what I claim and desire to secure by Letters Patent is:

- 10 1. In a toy-vehicle, a frame, wheels carried thereby, a platform pivotally secured to the frame, means operable by the movement of the wheels to rock the platform upon its pivotal support, a figure carried by said platform, arms carried by said figure, a yoke pivoted to said frame at its forward end, a link connecting said yoke and the arms of said figure, whereby said figure and said yoke will move in unison when said vehicle is propelled, a yoke-frame carried by the frame of the vehicle, an arm carried by said yoke-frame, a link connecting said arm and said platform, and a sound-producing element carried by said yoke-frame.
- 20 2. In a toy-vehicle, a frame open at one end thereof, a wheel carried by said frame and located in the open end thereof, a yoke carried by the supporting pin for said wheel and extending over said wheel, a pair of wheels located at the opposite end of said frame, an axle therefor, a crank-arm carried by said axle, a platform carried by and pivotally secured to the vehicle frame, a link connecting said platform and said crank-arm, a figure carried by said platform, a yieldable support for said figure, and a link connecting said figure and the yoke at the open end of the vehicle-frame.
- 30 3. In a toy-vehicle, a frame open at one end thereof, a wheel carried by said frame and located in the open end thereof, a yoke carried by the supporting pin for said wheel and extending over said wheel, a pair of wheels located at the opposite end of said frame, an axle therefor, a crank-arm carried by said axle, a platform carried by and pivotally secured to the vehicle-frame, a link connecting said platform and said crank-arm, a figure carried by said plat-

form, a yieldable support for said figure, a link connecting said figure and the yoke at the open end of the vehicle-frame, a support pivotally secured to the frame of the vehicle, a sound-producing element carried by said support, and means connecting said support and said table.

4. In a toy, a movable platform, means to impart movement thereto, a yieldable support carried by the platform, a figure carried by said yieldable support, a frame for said platform, a link secured at one end thereof to said figure, the other end of said link extending to the front end of the frame for said platform, and a support for said link carried by said frame at the front end thereof.

5. In a toy, a movable platform, means to impart movement thereto, a yieldable support carried by the platform, a figure carried by said yieldable support, a frame for said platform, a link secured at one end thereof to said figure, the other end of said link extending to the front end of the frame for said platform, a support for said link carried by said frame at the front end thereof, a handle for said frame, and resilient arms carried by said handle to releasably engage said frame.

6. In a toy-vehicle, a frame, wheels carried thereby, a platform pivotally secured to the frame, means operable by the movement of the wheels to rock the platform upon its pivotal support, a figure carried by said platform, movable arms carried by said figure, a yoke carried by the frame at its forward end, a link connecting the yoke and the arms of said figure, a yoke-frame also carried by and pivotally supported on the vehicle-frame, and means connecting the yoke-frame and platform, whereby the movement of the platform will move the yoke-frame in unison therewith.

Signed at New York city, N. Y., this 18 day of June, 1915.

JOHN L. MOORE.
